CHARLES W. FRANZHEIM, OF WHEELING, WEST VIRGINIA.

SPECIFICATION forming part of Design No. 23,748, dated October 30, 1894.

Application filed September 29, 1894. Serial No. 524,622. Term of patent 3½ years.

To all whom it may concern:

Be it known that I, CHARLES W. FRANZHEIM, a citizen of the United States, residing at Wheeling, in the county of Ohio and State 5 of West Virginia, have invented a new and original Design for Covered Dishes, of which the following is a specification.

The invention relates to a new and original design for covered dishes.

10 The object of the present invention is to provide an ornamental and attractive covered dish; and the essential feature resides in a covered dish having the handle of its cover, and the adjacent part of the latter, ornamented 15 with leaf work and flowers, and having its body portion ornamented at the ends with leaf work, and provided at the upper edges with ornamental scallops, and having an ornamented and scalloped base.

20 In the drawings:—Figure 1 is a side view of a covered dish showing my new and original design. Fig. 2 is a plan view. Fig. 3 is an end elevation.

Referring to the drawings, 1 designates a 25 covered dish or tureen having its upper edges 2 scalloped, and provided below the same with ornament. 1 scroll work 3.

The handles 4 of the dish are located at the ends, and have their upper faces ornamented with scrolls, and they are provided with oval 30 openings 5.

The ends 6 of the body of the dish are ornamented with leaf work as shown; and the base 7 is scalloped at the edges, and is ornamented with scrolls, and other ornamentation 35 as shown. The sides adjacent to the base are provided with lower swells or bulged portions 8.

The cover 9 is ornamented around the handle 11 with leaf work, and the handle is ornamented with flowers and leaf work.

It will be apparent that the covered dish presents an appearance which is ornamental and attractive.

What I claim is—

45 The design for a covered dish herein shown and described.

In testimony that I claim the foregoing as my own I have hereto affixed my signature in the presence of two witnesses.

CHARLES W. FRANZHEIM.
